(73) Assignee: **Brother Industries, Ltd.**, Nagoya (JP)

(57) **CLAIM**

(**) Term: **14 Years**

The ornamental design for an ink ribbon cartridge for printing device, as shown and described.

(21) Appl. No.: **29/128,496**

DESCRIPTION

(22) Filed: **Aug. 28, 2000**

FIG. 1 is a front view of the ink ribbon cartridge for printing device;

(30) **Foreign Application Priority Data**

FIG. 2 is a rear view thereof;

Mar. 31, 2000 (JP) 12-8270

FIG. 3 is a left side view thereof;

(51) **LOC (7) Cl.** **18-01**

FIG. 4 is a right side view thereof;

(52) **U.S. Cl.** **D18/12**

FIG. 5 is a top plan view thereof;

(58) **Field of Search** D18/12, 40, 56;
D14/471, 481, 483, 484; 400/208, 234

FIG. 6 is a bottom plan view thereof;

(56) **References Cited**

FIG. 7 is a top perspective view thereof from one side;

U.S. PATENT DOCUMENTS

FIG. 8 is a top perspective view thereof from another side;

D. 331,771 * 12/1992 Yoshihara D18/12
D. 383,743 * 9/1997 Suwa et al. D18/56
D. 420,696 * 2/2000 Yung et al. D18/12

FIG. 9 is a bottom perspective view thereof from one side; and,

FIG. 10 is a bottom perspective view thereof from another side.
